BLAST FURNACE DISCHARGE STRUCTURE

Albert Mohr, Jr., and John P. Grilli, Chicago, Ill.

Application October 25, 1946, Serial No. 705,618

12 Claims. (Cl. 266—38)

1

The current invention pertains to certain structural betterments and resulting accompanying functional advantages in a novel construction for the hearth portion of an iron blast-furnace which includes the provision of the slag-discharge conduit cooler, or so-called "cinder-notch" cooler, with an adapter, conformer, or regulator block or member to allow variations in the degree of elevation between the center-line of such slag-tube cooler and the center-line of the metal-discharge conduit or generally styled "iron-notch."

At the present time, an iron blast-furnace produces as much as 1500 tons of iron daily and these furnaces usually remain in operation for a period as long as five years.

As all of the material in the hearth portion of a blast-furnace is either in molten condition or in an incandescent state, it creates substantial wear of the lining of the hearth, the molten matter causing reactions with the refractory materials in the hearth and the incandescent abrasive coke producing wear on the lining.

The usual or customary fixed distance between the lower level of the iron-discharge notch and the higher elevation of the cinder-discharge notch would be satisfactory provided none of the indicated wear took place in the crucible, but, as the hearth is progressively fluxed and gradually eroded away, the volumetric capacity between the cinder-notch and the iron-notch becomes increasingly greater, and, in a relatively short time, the cinder-notch is at such a level that it does not draw off from the crucible a sufficient or adequate amount of the molten floating slag.

This results in wild, or too fast or irregular, casts of iron and makes it impossible to maintain a proper tapping hole, because the latter is made of fire-clay and the molten slag fluxes the fire-clay out and makes the hole so large that it is difficult to separate the iron from the slag and to have an orderly cast.

Where some of the slag is drawn off from the iron-notch rather than from the cinder-notch there have been many cases known in which, due to the large slag volume passing through the tapping hole, all of the brick-work at the face of the tapping hole was finally burned out and this, in time, resulted in very dangerous and costly break-outs around the tapping hole.

Accordingly, one outstanding object or paramount aim of the present invention is to provide simple and efficient means to overcome these substantial and in cases hazardous disadvantages, and this is accomplished by the employment of the new adapter means so that, when the fur-

2

nace is new, the cinder-notch can be placed at a suitably high elevation with such adapter positioned below it, and, when the furnace is old and the cross-section of the hearth has become enlarged, as indicated above, this cinder-notch or slag-delivery conduit can be placed at one or more lower levels by using the specified conformer means in the manner indicated hereinafter.

This decreases the height between the slag-discharge duct or pipe and the iron-notch and thereby establishes relations in elevation which will maintain a sufficient volume of molten slag to be withdrawn through the cinder-notch before the molten iron is discharged.

In order that those acquainted with this art may have a full understanding of this innovative invention and the benefits accruing from its employment, two preferred embodiments thereof have been illustrated in the accompanying drawings, forming a part of this specification, and have been described below in detail.

In these drawings:

Figure 1 is a fragmentary, central, vertical section through the wall of the hearth portion of an iron blast-furnace showing its passage therethrough accommodating its cooled cinder-notch or slag-discharge conduit with its associated novel adapter or elevation control block;

Figure 2 is an elevation of the inner surface of such portion of the furnace;

Figure 3 is a view similar to that of Figure 2 but with the slag-discharge conduit and its adapter or control block in reversed relation;

Figure 4 is a vertical, central section on line 4—4 of Figure 3;

Figure 5 is a view analogous to that of Figures 2 and 3 but with a modified or divided type of adapter;

Figure 6 is a view similar to that of Figure 5 but with the duplex adapter and the cinder-notch in different positions;

Figure 7 is a similar view of the two parts of the adapter separated and with the cinder-notch between them;

Figure 8 is an upright cross-section on line 8—8 of Figure 7;

Figure 9 is a fragmentary, central, vertical, longitudinal section through the slag-discharge conduit or cinder-notch;

Figure 10 is a cross-section on line 10—10 of Figure 9;

Figure 11 is an isometric projection of the adapter illustrated in Figures 1 to 4 inclusive on a smaller scale than that of Figures 9 and 10;

Figure 12 is a part-plan and partial section of the adapter of Figure 11, but on a larger scale;

Figure 13 is a perspective view of one of the two companion adapters shown in Figures 5 to 8 inclusive; and

Figure 14 is a partial plan-view and a partial section of the adapter portrayed in Figure 13, but on a larger scale.

Referring first to Figures 1 and 2 of the drawings, this slag-discharge portion of the brick furnace-wall has a uniformly longitudinally tapered passage or aperture 21 therethrough defined by suitable bricks 22, the top and bottom surfaces 23 and 24 of which passage have inner, uniformly, lengthwise - tapered, transversely curved, surfaces of like size and shape with the intermediate vertical sections 25, 25 plane or flat, each such sloping or converging curved surfaces 23 and 24 being in the form of a series or succession of semi-circles of regularly decreasing diameters.

Initially, the upper portion of such space 21 is occupied by a round, metal, correspondingly tapered, hollow, slag-discharge conduit or cinder-notch 26 (Figures 9 and 10) having embedded or cast therein a coiled water-pipe (Figures 9 and 10) through which cooling water is circulated, such liquid entering the coil through the external inlet 28 and discharging from the coil through the outlet 29.

At any vertical, transverse, cross-section through such member 26 both the external and internal surfaces thereof are circular although both taper lengthwise so that the outer face of element 26 conforms exactly to the top, inner surface 23 of passage 21 through the wall.

Maintaining or supporting such tubular part 26 in the elevated relation presented in Figures 1 and 2 is a transversely-curved metal adapter 31 of the shape and style shown in Figures 11 and 12, such member having embedded therein a pair of metal pipes 32 and 33 with external inlet and outlet connections 34, 35 and 36, 37 whereby cooling water may be pumped through either one or both of them to additionally cool the superimposed notch-cooler 26.

As is clearly depicted, the lengthwise tapered, top, concave surface 38 of element 31 is the exact counterpart of the convex undersurface of member 26 with which it is in direct engagement and intimate contact, throughout, and the under longitudinally tapered, convex, arcuate surface 39 of the adapter conforms exactly to the inner concave, sloping surface 24 of the passage 21 on which it rests to support the duct 26 above.

Thus, the two associated metal members 26 and 31 in the aperture 21 practically completely fill the latter.

Now, as the adjacent hearth portion of the furnace gradually internally increases or enlarges in volume, for the reasons indicated above, so that the location of the slag-pipe 26 is too high to properly perform its required slag-drainage function efficiently, the adapter 31 is temporarily removed from passage 21, the conduit 26 lowered to the bottom of such passage 21, which it then snugly fits, and the adapter is inverted and reinserted in the passage above the conduit which space it closely fits to effectively perform its cooling function, this arrangement being portrayed in Figures 3 and 4, and in which relation the slag-conduit is at a suitable level to adequately do its work of delivering the molten slag.

Obviously, in making this modification, the

connections to the cooling pipes in both members have to be changed to comply with their new positions.

From what precedes, it will be clear that the conduit 26 not only performs its cooling action but this is augmented by the additional cooling which it receives from the adapter regardless of which of its two positions it occupies.

In case it is desired to provide three different levels or elevations for the cinder-notch cooler 26 instead of two such positions, this can be readily accomplished by making the adapter in two parts or sections of like structure, shape and size, as presented in Figures 5, 6, 7, 8, 13 and 14.

Such adapter structure is composed of two, transversely-curved, cooling-pipe-equipped like members 41, 41 which may be used in superposed relation under the cinder-notch cooler 26, as shown in Figure 5, or with one member below 20 and the other above such conduit 26, as presented in Figure 7, or with both parts in position above the element 26, as depicted in Figure 6, thus affording three different positions of the conduit depending upon the locations of the parts of the 25 adapter.

It is noted that each of this pair of members, 41, 41, has its one concave surface shaped both lengthwise and crosswise to conform closely to the exterior surface of the conduit 26 and has 30 its opposite convex surface shaped to accurately fit either of the like curved surfaces 23 and 24 of the wall passage 21 or exactly fit the concave surface of its companion like member 41, the pair of elements 41, 41 when fitted together, as 35 presented in Figures 5 and 6, being unitedly of the same shape and size as those of the single adaptor 31. In other words, the duplex adaptor 41, 41 may be considered as the single adaptor 31 divided into a pair of companion parts 41, 41.

Obviously, when the two members of the adapter are superposed and in either position of Figures 5 and 6, they are the same in size and shape as the adapter 31 and perform its function were the latter in their place.

In the drawing, the individual cooling pipes for such smaller adapter members have been designated by the reference characters 42, 42, and, naturally, as the positions of such conforming blocks are changed the connections to their pipes will necessarily have to be modified as required by their new locations.

Those skilled in this art will readily understand that this invention is not necessarily restricted and limited to the precise and exact details of structure shown and described and that reasonable modifications may be resorted to without departure from the heart and essence of the invention.

60 We claim:

1. For use in association with a known hollow cinder-notch cooler occupying its passage through the wall of an iron blast-furnace of greater depth than the vertical dimension of the cooler thus 65 allowing variation of the height location of the latter, a novel adapter designed to occupy said passage either beneath and supporting said cooler in the top portion of said passage or in inverted condition in the top portion of said passage above the cooler in the bottom portion of said passage, the top and bottom external surfaces of said cooler conforming respectively to the top and bottom inner surfaces of said passage, one surface of said adapter conforming to both said external surfaces of said cooler and the opposite

surface of said adapter conforming to both said internal surfaces of said passage.

2. The novel adapter set forth in claim 1, in which all of said surfaces are transversely curved alike.

3. The novel adapter set forth in claim 1, in which all of said surfaces are transversely curved alike and longitudinally tapered in equal degree.

4. The novel adapter set forth in claim 1, having means to permit it to be cooled interiorly.

5. The novel adapter set forth in claim 1, in which said cinder-notch cooler and said adapter when combined are of such size as to completely block said passage.

6. The novel adapter set forth in claim 1, in which said adapter is of substantially the same length as said cooler.

7. The novel adapter set forth in claim 1, which, whether positioned below or above said cinder-notch cooler, is in direct contact therewith.

8. The novel adapter set forth in claim 1, in which all of said surfaces are transversely curved alike and longitudinally-tapered in equal degree, and in which said adapter whether employed below or above said cinder-notch cooler is in direct contact therewith.

9. For use in association with a known cinder-notch cooler occupying its passage through the wall of an iron blast-furnace of greater depth than the vertical dimension of the cooler, thus allowing variation of the height location of the latter, a novel adapter consisting of a plurality of like transversely-curved parts designed to be

used in superposed relation or individually in said passage either below or above said cinder-notch cooler, or in part below and in part above said cinder-notch cooler, to vary the height of the latter in said passage, the top and bottom surfaces of said cooler conforming respectively to the top and bottom surfaces of said passage, one surface of each of said adapter parts conforming to both surfaces of said passage, the opposite surface of each of said adapter parts conforming to the cooler.

10. The novel adapter set forth in claim 9, in which all of said surfaces are transversely-curved alike.

11. The novel adapter set forth in claim 9, in which all of said surfaces are transversely-curved alike and are longitudinally-tapered in equal degree.

12. The novel adapter set forth in claim 9, in which each of said adapter parts has means to permit it to be cooled interiorly.
